VICTORY PLAQUE

Filed Dec. 16, 1942

FIG. 1.

FIG. 2.

INVENTOR.

Joseph S. Jacobs

UNITED STATES PATENT OFFICE

135,285

DESIGN FOR A VICTORY PLAQUE

Joseph S. Jacobs, New York, N. Y.

Application December 16, 1942, Serial No. 109,166

Term of patent 3½ years

To all whom it may concern:

Be it known that I, Joseph S. Jacobs, a citizen of the United States, residing at 236 West 70th Street, Manhattan, in the county of Manhattan and State of New York, have invented a new, original, and ornamental Design for a Victory Plaque, of which the following is a specification, reference being had to the accompanying drawing, forming a part thereof.

In my drawing:

Fig. 1 shows a front view of my victory plaque embodying my present invention.

Fig 2 shows a plan view thereof.

I claim:

The ornamental design for a victory plaque, as shown.

JOSEPH S. JACOBS.
